UNITED STATES PATENT OFFICE.

SALLIE OTEY HENSLEY, OF KNOXVILLE, TENNESSEE.

STOVE.

964,913.

Specification of Letters Patent. Patented July 19, 1910.

Application filed January 25, 1910. Serial No. 540,001.

To all whom it may concern:

Be it known that I, SALLIE OTEY HENSLEY, a citizen of the United States, residing at Knoxville, in the county of Knox and State of Tennessee, have invented certain new and useful Improvements in Stoves, of which the following is a specification.

This invention relates to stoves and more particularly to gas stoves wherein there is combined all the advantages of dry and steam cooking.

This invention also contemplates the provision of an adjustable means whereby fumes and odors of the cooking may be conducted to the outer atmosphere.

A further object of the present invention is to construct a stove of the above described nature that will provide a single conduit for conducting escaping steam used in steam cooking and the fumes to the exterior atmosphere.

With the above and other objects in view this invention consists of the construction, combination and arrangement of parts all as hereinafter more fully described, claimed and illustrated in the accompanying drawings wherein:

Figure 1 is a front elevation of a stove constructed in accordance with the present invention, parts thereof being broken away to illustrate the arrangement of the fume conducting conduit and the arrangement with respect thereto of the steam cooking chamber and the escape therefor; Fig. 2 is a vertical section taken along line 2—2 of Fig. 1 parts thereof being broken away; Fig. 3 is a perspective view of the hood adapted to rest over the mouth of the cooking utensil and conduct the fumes therefrom; Fig. 4 is a bottom plan view thereof; Fig. 5 is a front elevation of the means whereby the hood is adjustable vertically; Fig. 6 is a top plan view of Fig. 5 illustrating the position of the pipes and supporting ring; Fig. 7 is a perspective view of the stove illustrating the attachments for the same and the pipe leading to the window.

Reference being had to the accompanying drawings, A indicates the base portion forming a compartment of a gas stove, said base portion being provided with the shelves 10 and the front portion 11 of fine wire netting such as is adapted to withstand the ravages of rats or mice. Access is obtainable to the base portion of the stove through the door 12 and inasmuch as the

lower portion is not in any way used for cooking or heating, the same may be used as a storage compartment for cooking utensils, supplying a substantially rat proof compartment convenient to the stove.

The top of the compartment A is supplied with the usual burners B of any desired number and size, the rear burners B' being double burners. Extending over the rear burners B' is a cabinet C, said cabinet extending entirely across the stove, having formed on the right hand side adjacent the burners, the warming closet 13, the baking compartment 14 and the broiling compartment 15. Superposed above the warming compartment 13 is the chamber 16 through which the conduit extending to the exterior atmosphere passes.

The cabinet C is spaced from the burners and is provided with the door 17 which provides access to the steam chamber 18, said steam chamber being provided with a series of perforated shelves 19. An opening 20 is provided in one side of the base directly over the left hand rear burner and has the tubular member or pipe 21 surrounding the same, said pipe having the bayonet slot 22 therein. A sleeve 23 is adapted to reciprocate vertically in said tubular member 21 through the instrumentality of the pin 24 operating in said bayonet slot. This sleeve 23 is adapted to form a hood over the boiler D resting on the burner heretofore mentioned and provides a means for conducting steam produced by boiling water in said boiler to the steam chamber 18 where the same circulates through the openings in the perforated shelves 19. When it is desired to use the burner for some other purpose, the sleeve 23 is raised through the instrumentality of the handle 25 and retained in such a position by the pin 24 being engaged in the horizontal portion of the bayonet slot 22, thus entirely freeing the burner for other purposes. If so desired, cooking may be done on said burner and the fumes conducted up through the steam chamber in a manner similar to the steam.

A conduit 26 formed in sections is placed in the compartment 16 over the warming chamber 13 and opens into the steam chamber 18 at one extremity, the opposite extremity extending to a window or similar opening and thence to the outer atmosphere. Located in one side of the steam chamber 18 and extending through the shelves 19 is the

sectional pipe 27, said pipe being attached by the band 28 to the wall, separating the compartments 13, 14 and 15 from the steam chamber. At the lower extremity of said conduit or pipe which is adjacent the lower shelf is an elbow 29, said elbow being adapted to conduct the pipe over the opening 30 which is superposed directly above the right hand rear burner. A section of pipe 31 then connects the elbow with the opening and extends partially therethrough, said pipe being split at 45 at its lower extremity to provide for a slight contraction and expansion thereof.

15 A band 32 of flexible material surrounds the lower extremity of the pipe on the exterior of the steam chamber 18 and is secured to the base of said steam chamber by the ears 33 riveted to said chamber. At one 20 extremity of the band are the ears or lugs 34 between which is pivoted the handle 35, said handle carrying at its inner extremity the cam 36. The opposite extremity of the band is passed under the cam and is riveted 25 thereto. Thus it will be seen that when the lever is set as shown in Fig. 6, the band will be tightened at the lower extremity of the pipe section 31, causing the same to contract. The contraction of the band causes a pressure 30 to be exerted on the band between said cam and the pipe section, causing the band to be retained in its tightened position and the lower extremity of the pipe section to remain contracted. When the handle 35 is thrown in the opposite direction to that 35 shown in Fig. 6, the band will be loosened and the lower extremity of the pipe section allowed to expand.

In Fig. 3 is illustrated a hood which is 40 adapted to fit over a vessel E resting on the right hand rear burner. This hood comprises a pipe sectional shank 37 adapted to reciprocate in the pipe section 31, said pipe 45 37 having at its lower extremity the flared hood portion 38. This flared hood is constructed having a series of overlapped spring sections 38', said sections being of such a construction that when a pressure is exerted or removed from the same, the diameter of the lower side of the hood will increase or decrease accordingly. To provide for the contraction and expansion of these sections 38', a collar or ring 39 is adapted to reciprocate thereon, being provided with the handles 40, said handles providing a means whereby the same may be raised and lowered without injury to the operator. The diameter of the hood being adjustable the same is adapted to fit over various sizes of cooking utensils within the limits of the spring 45 of the sections 38'. The provision of the band 32 to contract and expand the lower extremity of the pipe section 31, makes it possible to obtain a vertical adjustment of the hood adapting the same for use over ves-

5 sels of various heights. The steam in the chamber 18 passes through the conduit 26 as does the fumes from the pipe 27, said pipe abutting in the opening of the conduit. This construction makes it possible to use the 70 opening 20 as a means for conducting fumes from the articles cooked over the left hand rear burner and also permits the steam from the chamber 18 and the fumes from the vessel E to be conducted from the stove by one 75 conduit without the fumes in any way coming in contact with the articles being steamed in the compartment.

From the foregoing it will readily be seen that the present invention covers a stove 80 constructed in a convenient and useful manner, having all of the advantages of the previous cookers, and also provided with the hood to conduct fumes from cooking articles adjustable vertically and diametrically. A 85 stove of this nature is highly advantageous when it is desired to do several kinds of cooking on one stove, and also to provide a storage compartment in the same stove.

Having thus described the invention what 90 is claimed as new is:

1. In a stove, the combination with a steam chamber and means for conducting the steam circulated through said chamber to the exterior atmosphere, and means for 95 conducting the fumes of cooking through said chamber to said last mentioned means.

2. A stove of the class described, comprising a base portion, having a plurality of burners, a cabinet located over a portion of 100 said burners, a steam chamber constructed in said cabinet, a conduit opening into said chamber, and means whereby the fumes of cooking may be conducted through said chamber into the conduit aforesaid. 105

3. A stove comprising in combination, a steam chamber, an escape conduit co-operating with said steam chamber, vertically adjustable means for conducting steam to said chamber, said steam being adapted to circulate therethrough, and pass out said escape conduit, and means whereby the fumes of cooking may be conducted to said escape conduit independently of the steam. 110

4. In a stove, a steam chamber, vertically 115 adjustable means for conducting steam to said chamber, a conduit located adjacent to the top of said chamber for conducting both fumes and steam to the exterior atmosphere, and means whereby fumes may be conducted 120 through the chamber and to said conduit irrespective of the steam.

5. The combination with a stove, means for conducting fumes of cooking from above the burners thereof to the exterior atmosphere 125 comprising a hood adjustable diametrically and vertically in combination with a pipe or conduit.

6. In combination with a stove, of means for conducting fumes of cooking to the ex- 130

terior atmosphere comprising a hood constructed of spring sections adjustable diametrically.

7. In combination with a stove, of a steam chamber superposed thereabove, a boiler co-operating with said stove, vertically adjustable means for conducting steam generated in said boiler to the steam chamber, a conduit located in the top of said steam chamber for conducting fumes and steam to the exterior atmosphere, means for conducting

fumes through said steam chamber to said conduit independently of the steam, and means of conducting fumes from the cooking to said last named means comprising a ¹⁵ hood adjustable diametrically and vertically.

In testimony whereof I affix my signature in presence of two witnesses.
